UNITED STATES PATENT OFFICE.

AUGUST LE FEVRE, OF DETROIT, MICHIGAN.

DESIGN FOR A FLAG, PENNANT, SIGN, EMBLEM, OR ARTICLE OF SIMILAR NATURE.

57,533.

Specification for Design.

Patented Apr. 12, 1921.

Application filed October 2, 1918. Serial No. 256,610. Term of patent 7 years.

To all whom it may concern:

Be it known that I, AUGUST LE FEVRE, a citizen of the United States, residing at Detroit, in the county of Wayne and State of Michigan, have invented a new, original, and ornamental Design for Flags, Pennants, Signs, Emblems, or Articles of Similar Nature, of which the following is a specification, reference being had to the accompanying drawing, forming part thereof.

The figure is an elevation of a flag, showing my new design.

I claim:

The ornamental design for a flag, pennant, sign, emblem, or article of a similar nature, as shown.

AUGUST LE FEVRE.
